INVENTOR.
WALTER F. HEROLD.
BY
John M. Herold
ATTORNEY.

UNITED STATES PATENT OFFICE

WALTER F. HEROLD, OF UPPER MONTCLAIR, NEW JERSEY, ASSIGNOR TO THE BASSICK COMPANY, OF BRIDGEPORT, CONNECTICUT, A CORPORATION OF CONNECTICUT

CASTER

Application filed January 24, 1927. Serial No. 163,247.

The present invention relates to improvements in casters, and has for an object to provide a socket and pintle structure, in which pintle retaining means is provided at the base of the socket, so that the latter may be of any desired size or shape, without respect to the pintle shape or diameter. It is particularly proposed to provide pintle retaining means in the form of a loosely mounted spring ring, which during normal operation of the caster will be out of frictional gripping relation to the pintle, and will furthermore not be under tension, so that there will be no wear, deformation, or other action on the ring that might affect its pintle retaining functions. Another object is to provide such retaining means which will positively position and maintain the pintle in relation to its bearings in the socket, and by which an increased holding action is obtained, so that an appreciable pull upon the caster is required to remove it. A further object is to provide a structure in which the wear upon the ring during insertion and removal of the caster will be negligible, the ring having only momentary engagement over a small portion of the pintle.

A still further object is to provide an improved pintle structure, in which a grooved or shouldered part is provided for cooperation with the retaining means, without impairing the strength of the pintle, and in which the tension required in inserting and removing the pintle may be regulated and accurately proportioned by the shape of the shouldered part.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a side elevation of a caster socket, according to one embodiment of the invention;

Fig. 2 is a vertical sectional view thereof, showing the same inserted in a tubular furniture leg, and with the caster in place;

Fig. 3 is a bottom plan view of the socket; Fig. 4 is a vertical sectional view of a modified form of socket, according to the invention, showing the same secured in a wood furniture leg, and with the caster pintle in place;

Fig. 5 is a top plan view of the socket; and Figs. 6, 7 and 8 are views, partly in elevation and partly in section, showing several modified pintle constructions.

Similar reference characters indicate corresponding parts throughout the several figures of the drawings.

Referring to the drawings, and more particularly to Figs. 1 to 3 thereof, the embodiment of the invention shown therein is adapted for attachment to a tubular metal furniture leg or post 10, and comprises a peripherally flanged leg mount washer 11 provided in annularly spaced relation to its flange with diametrically opposed circumferential slits 12 and 13, the portion of the leg mount between said slits being depressed to form said slits into laterally extending slots for securing the spring frame ends, and provided centrally with a pintle receiving opening 14.

The spring frame comprises a truncated cone-shaped top portion 15 having a depressed cone-shaped center bearing 16, and side legs 17 joined to the top by an annular rounded shoulder portion 18, these legs being of circumferential cross-section and provided at their lower ends with inwardly offset contracted leg mount engaging portions 19 having laterally extending circumferential end flanges 20 bent outwardly therefrom. The spring frame is assembled with the leg mount by compressing the side legs to a point where the outer edges of the end flanges 20 will pass downwardly past the upper walls of the slots 12 and 13, whereupon they are expanded outwardly through said slots beneath the lateral under surface of the leg mount, the engagement of the portions 19 with said upper walls of the slots limiting the expansion of the spring frame legs to such extent that in the detached position, Fig. 1, the side legs are inclined outwardly toward their lower ends. In the inserted

position within the furniture leg the side legs are contracted so that they engage the under surface of the leg substantially over their entire outer surface, and exert an outward pressure to firmly retain the caster 5 mounting frame and leg mount, the lower end of the leg 10 being engaged within the peripheral flange of the leg mount. In this attached relation the end flanges 20 extend 10 directly beneath the lower end of the furniture leg.

The pintle retaining means of the invention is carried upon the leg mount 11, and in the present embodiment consists of a cup 15 member 21 having a central pintle receiving opening 22 in line with the opening 14, and secured by projecting ears 23 inserted through slots 24 in the leg mount and bent over upon the under surface thereof. Within the cup there is loosely engaged and retained a split spring ring 25, its inner diameter being smaller than that of the openings 14 and 22 and its outer diameter smaller than the inner diameter of the cup, this 25 spring ring adapted, as will hereinafter more fully appear, to retain the caster pintle by loose engagement within a grooved or shouldered portion thereof.

The detachable caster consists of the usual 30 horn 26 having a caster wheel 27 rotatably carried therein upon an axle 28, and having a pintle 29 secured in its upper transverse portion, the lower end of the pintle being provided with a flange or shoulder 30 engaging the upper surface of the horn. The pintle is 35 provided at its lower portion with an enlarged diameter portion 31 provided with an annular groove 32, and above the groove there is provided a portion 33 tapering from the upper edge of the groove to the upper smaller diameter portion of the pintle. At the upper end of the pintle there is provided a cone-shaped recess 34 adapted to engage the center top bearing 16 of the spring frame. The 40 diameter of the pintle is such that the upper portion will pass freely through the spring ring 25, while the tapered portion 33 will expand the ring until the latter comes into relation with the groove 32, whereupon it will 45 contract within the groove in loose or non-frictional relation therewith, and the caster will thus be held against dropping out of the leg. Its normal swiveling action while supporting the furniture, however, will be un- 50 impeded, while the ring is not under tension and is out of gripping contact.

It is obvious that with the present construction the upper portion of the pintle may be of any desired shape or diameter and that 55 the spring frame may be constructed without regard to such shape or diameter, and particularly it may be formed to engage the furniture in the most efficient manner, with a full fit, for instance, as shown in the present 60 embodiment. The grooved structure of the

pintle is such that no weakened area is produced, but on the contrary, the base of the pintle, where there is the most strain, is proportionately strengthened by the enlarged diameter portion.

In Fig. 4 I have illustrated a modification 70 adapted particularly for use in wood furniture legs, and comprising a tubular socket shell member 40 formed from flat sheet metal stock, folded upon itself, and providing a top portion 41 including a top center pintle bearing 42 in the form of an inverted cone-shaped indenture, the longitudinal meeting edges of the blank providing longitudinal seams 43 at opposed sides of the socket member. At the base of the socket member there is provided an annular outwardly bent shoulder 44 and an annular downwardly bent flange 45. The base member 46, cupped up from sheet metal stock, is provided with an inwardly bent bottom flange 47 and an upwardly bent bottom pintle bearing flange 48, the flange 47 being beveled inwardly from its point of contact with the flange 45. At the upper edge of the base there are formed 80 spaced upwardly projecting prongs 49, and between these are provided lug portions 50, adapted, as shown in Fig. 5, to be bent inwardly upon the upper surface of the shoulder 44 to secure the base to the socket member, the pintle retaining spring ring 51 being loosely disposed and retained in the annular space between the shoulder 44 and the flange 45, and the bottom pintle bearing flange 48.

The caster and pintle structure is similar 90 to that shown in the first described embodiment, the pintle having bearing at its upper end with the conical top bearing portion 41 of the socket, and at its lower end with the flange 48, and being retained in the socket by 95 loose engagement of the ring in the pintle groove 42, so that while the caster is thus retained against dropping out, the ring is not tensioned and is free of gripping contact.

In Figs. 6, 7 and 8 I have illustrated several 100 modified forms of pintles, these being adapted for production in a header, without additional machining operations. The pintle 52, shown in Fig. 6, is provided with a base flange 53 having a shouldered portion 54 disposed between it and the cylindrical surface of the pintle, the upper surface of this shoulder adapted to form the lower wall of the 105 pintle groove. A sheet metal collar is spun or otherwise suitably secured upon the pintle 110 above the shoulder 54, and includes a cylindrical portion 55 adjacent the shoulder and adapted to form the base of the groove, a shouldered portion 56 opposed to the shoulder 54 and adapted to form the upper wall of the groove, and a tapered portion 57 extending 115 from the shoulder 56 to the surface of the pintle.

In the embodiment shown in Fig. 7, a different 120 form of collar is provided, comprising 125

a cylindrical portion 58 and a tapered portion 59, bent downwardly from its upper edge, and inwardly against the portion 58 in spaced relation to its lower edge, to form the upper wall of the pintle groove.

5 In the embodiment shown in Fig. 8, an annular integral enlargement 60 is formed in the pintle in spaced relation to the shoulder 54, forming a ring expanding portion and the upper wall of the pintle groove.

10 The pintle structure, as disclosed herein, is adapted to determine the proportionate force required to insert or remove the pintle, the pitch of the tapered lead portion above the 15 groove determining the force required in inserting the pintle through the spring ring, while the upper wall of the groove determines the force required in removing it, the upper wall, as shown in Fig. 6, for instance, providing a greater resistance to removal than the 20 upper wall, as shown in Fig. 8.

I have illustrated and described preferred and satisfactory embodiments of the invention, but it will be obvious that changes may 25 be made therein within the spirit and scope thereof, as defined in the appended claims.

Having thus described my invention, what I claim and desire to secure by Letters Patent is:—

30 1. In a caster, or the like, the combination of a floor engaging element including a pintle having an annular recess and a side thrust bearing portion below said recess of larger diameter than said recess, and a pintle receiving element adapted to be secured to a furniture leg or the like having a bearing aperture adapted to be engaged by said bearing portion of the pintle, and including a pintle retaining spring ring loosely retained in said element adapted to be expended by said pintle during insertion and upon complete insertion to contract into said annular recess in loose untensioned relation therein, said ring being loosely rotatable in its pintle 35 retaining relation both with respect to the pintle and said pintle receiving element, said bearing portion of the pintle and said bearing aperture adapted to maintain a substantially vertical axial relation of said pintle to prevent side pressure on said spring ring.

40 2. In a caster, or the like, the combination of a floor engaging element including a pintle having an annular recess in proximity to its base, and a side thrust bearing portion below said recess of larger diameter than said recess, and a pintle receiving element adapted to be secured to a furniture leg or the like having a bearing aperture adapted to be engaged by said bearing portion of the pintle, and including a pintle retaining spring ring loosely retained in said element at its base adapted to be expended by said pintle during insertion and upon complete insertion to contract into said annular recess in loose untensioned relation therein, said ring being

loosely rotatable in its pintle retaining relation both with respect to the pintle and said pintle receiving element, said bearing portion of the pintle and said bearing aperture adapted to maintain a substantially vertical axial relation of said pintle to prevent side pressure on said spring ring.

45 3. In a caster, or the like, the combination of a floor engaging element including a pintle having an annular recess in proximity to its base and a side thrust bearing portion below said recess of larger diameter than said recess, and a pintle receiving element adapted to be secured to a furniture leg or the like having a bearing aperture adapted to be engaged by said bearing portion of the pintle, and including an annular portion constituting a spring retaining pocket, and a spring ring loosely retained in said pocket and adapted to be expanded by said pintle during 50 insertion and upon complete insertion to contract within said annular recess in loose untensioned relation therein, said ring being loosely rotatable in its pintle retaining relation both with respect to the pintle and said pintle receiving element, said bearing portion of the pintle and said bearing aperture adapted to maintain a substantially vertical axial relation of said pintle to prevent side pressure on said spring ring.

55 4. In a caster, or the like, the combination of a floor engaging element including a pintle having an annular recess in proximity to its base and a side thrust bearing portion below said recess of larger diameter than said recess, and a pintle receiving element adapted to be secured to a furniture leg or the like having a bearing aperture adapted to be engaged by said bearing portion of the pintle, and including an annular spring ring and a plurality of pocket forming elements adapted to be assembled axially with the spring ring loosely contained in the pocket formed thereby, and said ring adapted to be expanded by said pintle during insertion and upon complete insertion to contract within said annular recess in loose untensioned relation therein, said ring being loosely rotatable in its pintle retaining relation both with respect to the pintle and said pintle receiving element, said bearing portion of the pintle and said bearing aperture adapted to maintain a substantially vertical axial relation of said pintle to prevent side pressure on said spring ring.

60 Signed at Bridgeport, in the county of Fairfield, and State of Connecticut, this 18th day of January, 1927.

WALTER F. HEROLD.
